INTERNAL COMBUSTION MOTOR

George F. Callahan, Jr., Mount Lebanon, Pa.

Application May 9, 1935, Serial No. 20,527

16 Claims. (Cl. 123—122)

The invention pertains to internal combustion motors employed as a propulsion means for vehicles with specific reference to the arrest and regulation of the heat, radiated by the exhaust manifold, to be consumed by the intake manifold in order to be united with the combustion fuel.

In internal combustion motors employing oil as a combustion fuel it is found that, in sections of the country where the climatic conditions vary at unusual degrees of temperature, the oil employed as the fuel, becomes congealed and will not atomize sufficiently to allow the proper combustive mixture within the combustion chambers. It has also been found during warmer periods, in various sections of the country where the terrain is of varying altitudes that while ascending a relatively steep grade, the temperature of the air beneath the hood of a vehicle, as a result of the heated motor, will attain a somewhat sufficient degree of heat to atomize the fuel oil. Upon descending a similar grade, the temperature of the air beneath the hood will diminish to such a degree so as to cause the fuel to congeal thereby detrimentally decreasing the efficiency of the motor unit.

One of the objects of the present invention is the provision of a suitable mechanism adapted to maintain the proper degree of heated air to be mixed with the fuel oil.

Another object of the invention is the provision of a jacket to arrest the heat given off by the exhaust manifold.

Another object of the invention is the novel construction of the jacket so as to partially encase the intake manifold and the exhaust manifold.

A further object of the invention is the provision of means for selectively regulating the temperature of the air within the jacket.

These and other objects will become apparent to those skilled in the art from the following description together with the accompanying drawings which form a part of the present description; in which—

Figure 1 shows a side elevational view of an internal combustion motor, removed from a vehicle, embodying one form of the present invention.

Figure 2 shows a plan view of the motor unit shown by Figure 1.

Figure 3 shows an enlarged sectional view taken along the lines 3—3 of Figure 1.

Figure 4 shows a sectional view similar to that shown by Figure 3.

Figure 5 shows a side elevational view of a modification of the invention.

Referring now in detail to the drawings wherein like numerals refer to similar parts, the numeral 1 generally designates an internal combustion motor. The exhaust manifold 2, secured

to the motor 1 adjacent the top portion thereof and extending in a horizontal direction, has a portion 3 leading downwardly to the muffler (not shown) and thence to the atmosphere. The intake manifold 4, having a portion 4a spaced outwardly of the exhaust manifold and extending in a vertical direction through the plane of the exhaust manifold, leads to the carburetor 4b and thus to the combustion chambers. Mounted on the portion 4a of the intake manifold, in a plane 5 above the exhaust manifold 2, is a suitable air cleaner 5.

The jacket 6 employed to arrest the heat radiating from the exhaust manifold comprises a vertical side wall 7 positioned between the exhaust manifold 2 and the side of the motor unit 1 and has, adjacent the lower portion thereof, outwardly extending shields 1a adapted to straddle the ports 2a of the exhaust manifold. An angular bracket 8 secured to the side wall 7 has 10 a leg 8a overlying and attached to the motor cover 1a. The side wall 9, positioned outwardly of the intake manifold 4, like the side wall 7, extends in a substantially vertical direction from a position adjacent the lower portion of the exhaust manifold 2 to a position above the air cleaner 5. The side walls 7 and 9 are preferably of sufficient length, in a horizontal direction, so as to overlie the greater portion of the exhaust manifold the purpose of which will become apparent from the succeeding description. A machine screw 9a is employed to secure the side wall 9 to the portion 4a of the intake manifold 4.

Connecting the rear portion of the side walls 7 and 9 is a vertically disposed rear wall 10 intersecting the exhaust manifold and closing the rear portion of the jacket 6. The top wall 11, connecting the side walls adjacent the top edges thereof and forming a closure for the top portion of the jacket 6, comprises a substantially horizontal portion 12 spaced from and overlying the air cleaner 5, a downwardly projecting portion 13 extending outwardly from the portion 12 and a portion 14 overlying the exhaust manifold in spaced relation thereto. An opening 13a is provided in the downwardly projecting portion 13 of the top wall 11, the purpose of which will be hereinafter described. The portion 14 of the top wall is inclined at an angle to the exhaust manifold thereby increasing the cross sectional 50 area of the front portion of the jacket to insure the freer passage of heat, radiating from the exhaust manifold, to reach the air cleaner 5. The inclined portion 14 further functions as a baffle plate in order to direct cool air, driven rearwardly 55 by the fan 1b, toward the opening 13a in the portion 13. The side walls 7 and 9 and the portion 13 of the top wall 11 merge, adjacent the front portion of the jacket, to form a front wall 15 which has, extending therefrom, a flange 16 60

adapted to rest upon the exhaust manifold 2. The band 16a encircling the exhaust manifold secures the flange 16 in position.

The bottom wall 17, extending inwardly of the 5 jacket from the lower edge of the side wall 9, follows the contour of the exhaust manifold thereby partially closing the bottom portion of the jacket 6. An aperture 17a is provided in the bottom wall 17 for the reception of the vertical portion 4a of the intake manifold.

It will become apparent to those skilled in the art that the jacket 6, by partially encasing the exhaust manifold 2 and the intake manifold 4, will retain an appreciable amount of heat radiating from the exhaust manifold thereby increasing the temperature of the air to be consumed by the intake manifold and consequently allowing the proper vaporization of the fuel oil within the combustion chambers.

20 During the summer months, the heat radiated by the exhaust manifold may be in excess to the amount required for the proper vaporization of the fuel oil and, with this in mind, a shutter arrangement (Figures 3 and 4) has been incorporated in the jacket so that the temperature of the air within the jacket may be regulated accordingly. The shutter arrangement is preferably mounted on the downwardly projecting portion 13 of the top wall 11 adjacent the edges of the opening 13a and comprises a frame member formed of spaced angular plates 18 and spaced Z-shaped closing pieces 19 and 20 respectively extending between the plates 18. Spaced at intervals along the angular plates 18 are bars 21 pivotally mounted in and extending through the angular plates 18. Substantially flat plates 22, extending between the plates 18 and secured to the bars 21 are, in normal position, arranged in overlapped relation to each other and have portions underlying the flange 23 of the closing piece 19 and overlying the flange 24 of the closing piece 20. Thus the frame member formed by the angular plates 18 and closing pieces 19 and 20 together with the plates 22 forms a closure for the opening 13a in the top wall 13 thereby preventing the escape of heated air from within the jacket 6.

50 The links 25, secured to the bars 21 adjacent the one end thereof, are pivotally connected to the operating lever 26 by means of the pins 27. Pivotally mounted on the side wall 7 of the jacket is a bell crank 28 having an arm 29 connected to the angularly disposed leg 26a of the operating lever 26 by means of the rod 30. The control rod 31, adapted to move in a horizontal direction, is pivotally secured to the arm 32 of the bell crank 28 and extends to a suitable mechanism (not shown) whereby the shutter arrangement may be operated either manually or thermostatically.

65 In order to inform the operator of the motor regarding the degree of heat within the jacket, a temperature indicating bulb 33 is secured to the portion 12 of the top wall 11 and extends into the jacket 6 and air cleaner 5. This bulb is connected to a suitable registering dial (not shown) by the conducting rod 33a.

70 The operation of the shutter arrangement is as follows; assuming the temperature within the jacket has reached an excessive degree and it is desired to alleviate this condition by opening the shutter and thereby allowing the entrance of cool air, being directed rearwardly by the fan 1b, to enter the jacket. The control rod 31 is

80 moved in a horizontal direction toward the rear of the jacket. This movement will impart a counter clockwise motion to the bell crank 28 thereby raising the rod 30 and the operating lever 26.

85 The movement of the operating lever 26 in a substantially vertical direction will cause the rotation of the links 25, bars 21 and plates 22 in a counter clockwise direction thereby positioning the plates 22 horizontally as shown by Figure 4.

90 In order to reduce the temperature of the air within the jacket more rapidly a modification of the invention is disclosed by Figure 5. The modified jacket 35 is substantially similar to the jacket 6 disclosed by Figures 1 to 4 both inclusive excepting that an additional shutter arrangement 36 has been positioned on the rear wall 37. When the shutter arrangements 36 and 38 are in opened position, the relatively cool air directed rearwardly by the fan will create a draft through the top portion of the jacket encasing the air cleaner carrying the heated air out of the jacket 37.

95 The shutter arrangement 36 is opened and closed by means of a rod 39 connecting the operating lever 40 and the bell crank 41. The bell crank 41, which is pivotally mounted on one side of the jacket 35 is connected to the arm 32a of the bell crank 28a by means of the intermediate rod 42. The operating mechanism for the shutter arrangement 38 is the same as heretofore described for the shutter arrangement shown in enlarged views by Figures 3 and 4 and it will only be necessary to describe the operation of the shutter arrangement 36. When the control rod 31a is moved in a horizontal direction toward the rear of the jacket 35 the bell crank 28a will rotate in a counter clockwise direction moving the intermediate rod 42 toward the shutter arrangement 36. This movement will impart a clockwise motion to the bell crank 41 which in turn will move the rod 39 and operating lever 40 in a vertical direction causing the plates 22a to assume an open or horizontal position.

100 It will be obvious to those skilled in the art that various alterations may be made to the present invention as shown in the drawings and described in the present specification as this construction was shown and described merely as a means of exemplification.

Having thus described the invention what I claim as new and desire to secure by Letters Patent is:

1. In an internal combustion motor, in combination, a horizontally disposed exhaust manifold, a vertically disposed intake manifold spaced outwardly of the exhaust manifold, a jacket partially enclosing said manifolds; said jacket having spaced side walls, a rear wall connecting the side walls, a top wall overlying the manifolds in spaced relation thereto and a shutter arrangement on the top wall for selectively controlling the temperature within the jacket.

2. In an internal combustion motor, in combination, a horizontally disposed exhaust manifold, a vertically disposed intake manifold spaced outwardly of the exhaust manifold, a jacket partially enclosing said manifolds; said jacket having spaced side walls, a rear wall connecting the side walls, a top wall having portions in different planes and overlying said manifolds in spaced relation thereto and means for selectively controlling the temperature within the jacket.

3. In an internal combustion motor, in combination, a horizontally disposed exhaust mani-

fold, a vertically disposed intake manifold spaced outwardly of the exhaust manifold, a jacket partially encasing said manifolds; said jacket having spaced side walls, a rear wall connecting the side walls, a top wall having portions in different planes and overlying said manifolds in spaced relation thereto and a shutter arrangement on said top wall for selectively controlling the temperature within the jacket.

10. 4. In an internal combustion motor, in combination, a horizontally disposed exhaust manifold, a vertically disposed intake manifold spaced outwardly of the exhaust manifold, a jacket partially encasing said manifolds; said jacket having spaced side walls, a rear wall connecting the side walls, a top wall having portions in different planes and overlying said manifolds in spaced relation thereto, a shutter arrangement on said top wall and a shutter arrangement on said rear wall for selectively controlling the temperature within the jacket.

15. 5. In an internal combustion motor, in combination, a horizontally disposed exhaust manifold, a vertically disposed intake manifold spaced outwardly of the exhaust manifold, a jacket partially encasing said manifolds; said jacket having spaced side walls, a rear wall connecting the side walls, a top wall overlying said manifolds in spaced relation thereto, a shutter arrangement on said top wall and a bell crank pivotally mounted on one of the side walls and connected to the shutter arrangement.

20. 6. In an internal combustion motor, in combination, a horizontally disposed exhaust manifold, a vertically disposed intake manifold spaced outwardly of the exhaust manifold, a jacket partially encasing said manifolds; said jacket having spaced side walls, a rear wall connecting the side walls, a top wall overlying said manifolds in spaced relation thereto, a shutter arrangement secured to the top and rear wall for selectively controlling the temperature within the jacket and a temperature indicator secured to the top wall and extending within the intake manifold for registering the temperature within the jacket.

25. 7. In an internal combustion motor, in combination, an exhaust manifold, an intake manifold, an air cleaner secured to the intake manifold, a jacket encasing the air cleaner and partially encasing the exhaust and intake manifolds and a mechanism secured to the jacket for selectively regulating the temperature within the jacket.

30. 8. In an internal combustion motor, in combination, a horizontally disposed exhaust manifold, an intake manifold having a portion extending above the plane of the exhaust manifold and a jacket; said jacket having a top wall overlying the intake manifold and projecting downwardly in spaced relation to the exhaust manifold and means secured to the top wall for selectively regulating the temperature within the jacket.

35. 9. In an internal combustion motor, in combination, an exhaust manifold, an intake manifold and a jacket partially encasing the exhaust and intake manifolds; said jacket having spaced side walls, a top wall overlying said manifolds in spaced relation thereto and connecting the side walls, and a shutter arrangement secured to the top wall adapted to selectively control the temperature within the jacket.

40. 10. In an internal combustion motor, in combination, an exhaust manifold, an intake manifold and a jacket partially encasing the exhaust and intake manifolds; said jacket having spaced side walls, a rear wall connecting the side walls, a top wall overlying the exhaust and intake manifolds and connecting the side walls, and means secured to the top and rear walls adapted to control the temperature within the jacket.

45. 11. In an internal combustion motor, in combination, an exhaust manifold, an intake manifold and a jacket partially encasing the exhaust and intake manifolds; said jacket having spaced side walls, a rear wall connecting the side walls, a top wall overlying the exhaust and intake manifolds, a shutter arrangement secured to the top and rear walls, and bell cranks pivotally secured to one of the side walls and pivotally connected to the shutter arrangements.

50. 12. In an internal combustion motor, in combination, an exhaust manifold, an intake manifold and a jacket partially encasing the exhaust and intake manifolds; said jacket having spaced side walls, a top wall overlying the exhaust and intake manifolds, a shutter arrangement secured to the top wall, a bell crank pivotally secured to one of the side walls and connected to the shutter arrangement, and a rod pivotally secured to the bell crank adapted to control the opening and closing of the shutter arrangement.

55. 13. In an internal combustion motor, in combination, an exhaust manifold, an intake manifold, a jacket partially encasing the exhaust and intake manifolds; said jacket having spaced side walls, a rear wall connecting the side walls, a top wall having portions in spaced vertical planes overlying said manifolds, and means for selectively controlling the temperature within the jacket.

60. 14. In an internal combustion motor, in combination, an exhaust manifold, an intake manifold, a jacket partially encasing the exhaust and intake manifolds; said jacket having spaced side walls, a rear wall connecting the side walls, a bottom wall extending inwardly of the jacket from one of the side walls, a top wall overlying the manifolds and connecting the side walls, and means secured to said top wall for selectively controlling the temperature within the jacket.

65. 15. In an internal combustion motor, in combination, an exhaust manifold, an intake manifold, an air cleaner secured to the intake manifold, a jacket encasing the air cleaner and partially encasing the exhaust and intake manifolds, and a shutter arrangement secured to the jacket for selectively regulating the temperature within the jacket.

70. 16. In an internal combustion motor, in combination, an exhaust manifold, an intake manifold, a jacket partially encasing the exhaust and intake manifolds; said jacket having spaced side walls, a rear wall connecting the side walls, a bottom wall extending inwardly of the jacket from one of the side walls, a top wall overlying the manifolds and connecting the side walls, and a shutter arrangement secured to the top and rear walls for selectively regulating the temperature within the jacket.
